DETACHABLE SPRING-ANCHORING MEANS

Ferdinand Fengler, Bristol, Conn., assignor to
The E. Ingraham Company, Bristol, Conn., a
corporation of Connecticut

Application August 22, 1946, Serial No. 692,325

1 Claim. (Cl. 58—52)

1

The present invention relates in general to timepieces and more especially to timepieces having improved spring-anchoring means adapted to secure the outer free end of the mainspring or alarm-spring of the timepiece to its frame.

Heretofore the free or outer ends of the mainspring and alarm-spring of timepieces of the class commonly known as alarm clocks have been made fast by securing the outer ends of the springs to one of the pillars of the frame, the securing-means being quite generally a clamp-member which is adapted to encircle one of the pillars of the frame and to be secured to the free end of the spring by a rivet. This construction is not only relatively expensive, but necessitates that the entire frame of the timepiece be disassembled to repair or replace a broken spring.

An object of the present invention is to provide improved means for anchoring the outer free end of a spring to the frame of a timepiece.

A further object is to provide a detachable spring-anchoring means which will enable the free end of the spring to be readily secured to and disengaged from the frame of the timepiece without disassembling the frame.

A still further object of the invention is to provide a detachable element of the frame which is constructed so as to lockingly engage in an aperture in the outer free end of the mainspring to anchor the spring to the frame of the timepiece.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a fragmentary plan view of the frame of a timepiece embodying the improved spring-anchoring means of this invention;

Fig. 2 is a front elevation of the frame showing the spring-anchoring means of Fig. 1; and

Fig. 3 is a fragmentary sectional view on the line 3—3 of Fig. 1.

Referring to the drawings which illustrate an exemplary embodiment of the invention, the timepiece-frame is indicated generally at 10 and comprises front and rear movement-plates 11 and 12 held in spaced parallel relationship by pillars 13. Mounted between the front and rear movement-plates are gear trains comprising a time-train, indicated generally at 14, and an alarm-

train indicated generally at 15. The time-train 14 is one of conventional construction and is driven by the force of a wound spiral mainspring such as shown at 16, the latter being supported on a winding-arbor 17. Heretofore the mainspring of timepieces of the class referred to have been supported on the winding-arbor between the front and rear movement-plates, which construction has required a frame of relatively-large dimension from front to back. In the present embodiment, however, as seen in Fig. 2, the mainspring 16 is mounted on the winding-arbor 17 so that its upper face 160 lies in a horizontal plane above the horizontal plane of the rear movement-plate 12, the edge 120 of the rear movement-plate 12 adjacent the mainspring 16 being made arcuate in shape so as to provide clearance for and to accommodate the inner convolutions of the mainspring 16. This construction permits the use of a relatively-thin frame-structure.

The lower or forward end of the winding-arbor 17 is rotatably mounted in the front movement-plate 11. The upper or rear end of the winding-arbor is shown journaled in a bearing-aperture 18 formed in a detachable element of the frame indicated generally at 19, the rear extremity of the winding-arbor 17 being provided with the usual winding-key 20 for manually rotating the arbor 17. The mainspring 16 is secured at its inner end 21 to the winding-arbor 17, the connection between the inner end of the spring and the arbor being the usual type of fastening-means 22, as shown in Fig. 2.

The opposite or outer free end 23 of the mainspring 16 is adapted to be anchored to the frame 10 in a manner such as to enable the outer end 23 of the spring to be readily attached thereto and removed therefrom with dispatch and without necessitating the disassembly of the entire frame. To this end, the outer extremity of the mainspring is preferably reduced in width, as shown in Fig. 3, the reduced portion constituting a tongue 24 having a radius at its outer end and a longitudinal slot 25. The slot 25 is substantially rectangular and closed at both ends, its longitudinal axis being coincident with the longitudinal axis of the tongue 24.

Referring to the detachable element 19 of the frame, the latter comprises a substantially-straight bracket or bridge-member of a length to span the clearance space provided by the arcuate edge 120 of the rear movement-plate and superposed on the top surface thereof, the opposite ends of the bridge-member 19 being secured thereto by suitable fastening-means 31 of the re-

spective posts 13 of the frame. As shown in Fig. 1, the bracket or bridge-member 19 is substantially triangular in shape, its base 26 being substantially parallel with the corresponding opposite edge (not shown) of the frame. The opposite ends of the bridge-member constitute relatively-narrow arm-portions 27 having rounded ends, the peripheries of which blend substantially tangentially into the base 26 of the triangle. The intersection of the periphery of each end 27 with its corresponding sloping side 28 of the bridge-member 19 constitutes an abrupt shoulder 29, for the purpose hereinafter described. The portion of the bracket 19 intermediate the arms 27 is struck up to provide an elevated substantially-planar bridge 30 which is provided with the aforesaid bearing-aperture 18 in which the upper end of the winding-arbor 17 is journaled, the bridge 30 constituting, in effect, a bearing-plate for the winding-arbor.

Referring to Fig. 3, the arms 27 of the bridge-member are not quite so wide as the length of the rectangular slot 25 in the tongue 24 of the mainspring and are slightly less thick than the width of the tongue-aperture 25, as a consequence of which the apertured-tongue 24 of the mainspring is adapted to be slipped over one arm 27 of the bracket-member and to be lockingly engaged therewith. As will be seen from Fig. 1, the normal tendency of the outer end 23 of the mainspring 16 is to unwind in a counterclockwise direction, but any tendency for the outer end of the spring to unwind is prevented by abutment of the outer end of the spring with the shoulder 29 of the respective arm 27; and engagement of the shoulder 29 at the closed end of the slot 25 with the adjacent outer edge of the respective arm 27.

As pointed out above, the bracket 19 is adapted to be detachably secured to the frame 10 by fastening-means which, as shown in Fig. 2, comprises upwardly-projecting threaded-extensions 32 of the posts 13 arranged to extend through suitable apertures 33 in the respective arms 27 of the bracket, the apertured arms 27 being secured to the threaded-extensions 32 by suitable nuts 34. In the event the mainspring 16 breaks or should have to be removed for any other reason, the bracket or bridge-member 19 may be readily unfastened from the frame 10 of the timepiece by removing the nuts 34 of the posts 13, whereupon the apertured end 23 of the spring may be slipped off of its corresponding arm 27 of the bracket without disassembling the frame 10.

Although the preferred spring-anchoring structure is the bridge-like bracket-member 19 shown

55

in the drawings and which has the additional function of a bearing-plate for the winding-arbor 17, it is within the purview of this invention to anchor the apertured end of the spring 16 to a bracket which is detachably secured to one of the posts 13 in the manner described above, or to some other part of the frame 10, but which is independent of the bridge-like bracket-member 19.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claim are intended to be embraced therein.

I claim:

20 In a timepiece having a frame, including a rear movement-plate having a recessed edge; a gear-train mounted in said frame; a spring for driving said gear-train, said spring having a longitudinal aperture at its outer end; a spring-winding arbor; means to secure the inner end of said spring to said winding-arbor to support said spring in said frame in juxtaposition to the recessed edge of said rear movement-plate with a portion of said spring extending rearwardly of the plane thereof; and means to anchor the outer end of said spring comprising a bracket-member arranged to span the recessed edge of said rear movement-plate and having arm-portions at opposite ends thereof and an intermediate bridge-portion, said arms being arranged to detachably secure said bridge-portion to said rear movement-plate and one of said arm-portions engaging in the longitudinal aperture of said spring in a plane substantially at right angles to the plane of the outer end thereof to anchor the outer end of the spring, said bridge-portion overlying the rearwardly-extending portion of said spring and constituting a bearing support for the outer end of said winding-arbor.

FERDINAND FENGLER.
